MACHINE FOR SHRINKING HAT BATS

Frank L. Schmeltz, Danbury, Conn., assignor to
United States Hat Machinery Corporation, New
York, N. Y., a corporation of Virginia

Application November 17, 1937, Serial No. 175,051

4 Claims. (Cl. 28-9)

The present invention relates to the shrinking of felt hats—for example, bats from which felt hats are made—and it has particular reference to the method of and a machine for effecting the starting operation on the hat bats; this operation following the hardening of the hat in the usual manner. While the invention is particularly adapted for use in the starting operation, it is not limited thereto.

An object of the present invention is to provide an improved machine and method by which hat bats and the like may be economically, effectively, and correctly started preliminary to subsequent felting or shrinking operations requiring a more severe action.

A further object is the accomplishment of this starting by a machine wherein the hat bats are subjected to a series of blows, some of which are relatively more rapid than others; the hat bat being rotated so that it is simultaneously subjected to the two types of blows.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings which illustrate one embodiment which the present invention may take:

Figure 1 is a plan view of the machine;

Fig. 2 is an end view thereof; and

Fig. 3 is a somewhat diagrammatic end view showing the cages and pressure rolls with the hat bat therebetween.

Referring to the drawings, the machine has a suitable frame 9 in which are mounted, on parallel axes, cages A and B; the cages being so shaped as to form a pocket or seat therebetween adapted to receive the roll C of bats to be manipulated. The cages are respectively carried by shafts 10 and 11; shaft 10 being provided at one end with a pulley 12 which may be belt-driven to operate the machine. The opposite end of shaft 10 is provided with a gear 13 which meshes with an idler 14 which, in turn, meshes with a gear 15 on the end of shaft 11. In this way, when pulley 12 is rotated to turn shaft 10 in a counterclockwise direction, shaft 11 will be rotated simultaneously in the same direction through the gear chain 13, 14, and 15.

In accordance with the present invention, cage A is provided with a pair of oppositely disposed

heads 16 which are secured to the shaft 10 and are interconnected by a plurality of longitudinally extending rods 17 which preferably have a circular cross section. In the embodiment shown, cage A is provided with thirty-two of 5 these rods, although this number may vary according to the size of the machine. The rods are spaced apart a distance approximately equal to a radius thereof.

The cage B is similarly formed with oppositely 10 disposed heads 18 and a plurality of interconnecting longitudinal rods 19 also preferably of circular cross section. However, the rods 19 are of larger diameter than the rods 17 of cage A; the cage B in this instance being provided with 15 twenty such rods; the rods being spaced apart a distance approximately equal to the radius thereof. With this arrangement, the ratio of rods on cage A to that of cage B is approximately three to two, and, as a result, when the hat bat C rests 20 in the pocket therebetween, the periphery thereof will be simultaneously engaged by more of the rods 17 of cage A than of the rods 19 of cage B.

In order to maintain the bats C in contact with the rolls, there are provided pressure rolls 25 20 and 21. These rolls are automatically raised and lowered in timed relation to the stopping and starting of the machine, as hereinafter described in detail. In the present illustrative disclosure, the roll 20 is carried by a pivoted frame 30 or carrier comprising a pair of arms 22 fixed to a rock shaft 23 journaled in brackets 36. The other pressure roll 21 is carried by a shaft 24, the ends or gudgeons of which extend into vertical slots provided in the arms 22.

Means are provided for permitting adjustment 35 of the pressure rolls so as to accommodate rolls of bats of various sizes. To this end, one of the arms 22 is adjustably connected to a lever or link 37 which is mounted on the shaft 23 for angular adjustment. One end of the lever 37 is pivotally connected to a yoke member 38. The adjustable connection between the arm and the lever 37 consists of a bolt 39 carried by the lever and extending through a slot 40 in the arm. 40

The numeral 45 designates a cam shaft on which are mounted the instrumentalities for controlling the clutch sleeve 34 and the movement of the arms 22 to and from operative position. This cam shaft is driven from the cage 50 shaft 10 through the train of gears 46, 47, 48, and 49. The gear 49, which is fixed to the cam shaft, has, on its outer face, a projection or trip 51 which is adapted to engage a projection 51 on the cam lever to throw this lever in a direc- 55

tion to disengage the clutch after the machine has been in operation for a predetermined time. Fixed to the cam shaft 45 is a cam 55 which is adapted to engage a roller 56 on the lower end 5 of the yoke 38 so as to raise the pressure rolls to the dotted line position shown in Fig. 2 just before the trip 50 disengages the clutch 34.

The operation of the machine is as follows: The bats, in moistened condition, are rolled up 10 in the usual manner in a piece of burlap or flannel—that is, four to eight bats are laid one upon the other on the flannel and rolled up from tip to brim. The rolled assembly is placed in the trough between the two cages in such position 15 that, when the machine is in operation, the tendency will be to wind the assembly tighter. The clutch is now thrown in by operating the clutch lever 35 through the instrumentality of the handle 35a whereupon the cages will be driven, and 20 the cam 55 will move out of engagement with the roller 56 so that the pressure rolls will move from the inoperative position shown in dotted lines to the operative position shown in full lines, Fig. 2. After a predetermined time, say after 25 the machine has been running for twelve seconds with the cages rotating at 56 R. P. M., the cam 55 raises the pressure rolls, and then the trip 50 throws the clutch so as to stop the machine. The roll of bats is taken from the machine, unrolled, turned over bottom side up, and 30 again rolled up from tip to brim and the re-wound assembly is placed in the machine and the operation repeated, after which the bats are rolled from one side to the other and placed back 35 in the machine and then operated upon. Next, the bats are turned over bottom side up and again rolled from side to side and manipulated in the machine in this condition. The four operations—that is, "two tips and two side rolls"— 40 are called a "round." The bats are now opened out flat and each bat is crozed or folded at a different place and then the bats, which have been on the outside, are placed in the center, and the center bats are placed on the outside so as 45 to make a new pile for the second round.

During the operation of the machine, the rods of cage A give the bat a rapid, but shallow, punching motion, and there is formed therein 50 a wave comprising crests adjacent each contacting rod and troughs intermediate of each contacting rod. Simultaneously, the cage B, though rotating at a like speed, subjects the bat to a slow, but deep, punching motion because of the fewer rods of greater diameter. As only two 55 of the rods 19 will be contacting the bat, the resultant wave will be of greater amplitude; there being formed but two crests and one trough. As the bat is rotated, the portion acted on by the rods of cage A is subsequently acted upon by 60 the rods of cage B whereupon the felting motion resulting from the punches of cage A will be distributed over a different range and subjected to a different type of blow than when in contact with cage A. Thus, the cages, in effect, act upon 65 the bats with a continuous wave-like or corrugated surface, and the bat is simultaneously subjected to two different waves, one creating rapid shallow blows and the other slow deep blows, and

each part of the bat successively receives each type of blow as it is rotated, thus maintaining a vibratory action which effects a shrinking of the bats.

Despite the difference in the size of the rods, 5 the action of the machine is very smooth, elastic, and gentle, and avoids "shoves" and defective work. The spacing of the rods is of importance; it being necessary that they be so spaced that the bat will be in contact with a substantial 10 area thereof at all times; this being obtained, in the present instance, by the narrow spacing between the succeeding rods. Thus, the machine will operate with a uniformity of pressure and motion on the bat. 15

As many changes could be made in the above construction and many apparently widely different embodiments of this invention could be made without departing from the scope thereof, 20 it is intended that all matter contained in the above description or shown in the accompanying drawings shall be interpreted as illustrative and not in a limiting sense.

It is also to be understood that the language used in the following claims is intended to cover 25 all of the generic and specific features of the invention herein described and all statements of the scope of the invention which, as a matter of language, might be said to fall therebetween.

I claim as my invention:

1. In a machine of the character described, a pair of cages arranged to support a roll of bats, each of said cages comprising a pair of spaced heads and longitudinally extending rods supported by said heads and spaced relatively close to 35 one another; the rods of one of said cages being of a greater diameter, but less in number, than the rods of the other cage.

2. In a machine of the character described, a pair of parallel cages arranged to support a roll 40 of bats, each of said cages comprising a pair of spaced heads and longitudinally extending rods supported by said heads, the rods of one cage being of larger diameter than the rods of the other cage, and the other cage having a number 45 of rods in excess of the first cage in an approximate ratio of three to two.

3. In a machine of the character described, a pair of parallel cages arranged to support a roll 50 of bats, each of said cages comprising a pair of spaced heads and longitudinally extending rods supported by said heads and spaced relatively close to one another, the rods of one cage being of a larger diameter but of a lesser number than the rods of the other cage, and means for exerting 55 pressure upon the roll of bats supported between said cages.

4. In a machine of the character described, a pair of parallel cages arranged to support a roll 60 of bats, each of said cages comprising a pair of spaced heads, and longitudinally extending rods supported by said heads and spaced relatively close to one another; the rods being of a larger diameter but of lesser number than the rods of the other cage and the spacing between the rods 65 being less than the diameter of the rods.
